TIRE

Charles C. Custer, Akron, Ohio, assignor to The
B. F. Goodrich Company, New York, N. Y., a
corporation of New York

Application January 31, 1951, Serial No. 14,049

Term of patent 14 years

(Cl. D90—20)

To all whom it may concern:

Be it known that I, Charles C. Custer, a citizen of the United States of America residing at Akron, in the county of Summit and State of Ohio; have invented a new, original, and ornamental Design for a Tire of which the following is a specification, reference being had to the accompanying drawing forming a part thereof.

In the drawing:

Fig. 1 is a perspective view of a tire, embodying my new design.

Fig. 2 is a detailed fragmentary view of the tread of the tire to a larger scale.

I claim:

The ornamental design for a tire, as shown.

CHARLES C. CUSTER.
